Primary Examiner — Nathan M Johnston(74) *Attorney, Agent, or Firm* — Cao Intellectual Property Services, LLC; Veronica-Adele R. Cao(57) **CLAIM**

The ornamental design for a spherical toothbrush holder, as shown and described.

DESCRIPTION

FIG. 1 is a perspective view of a spherical toothbrush holder, showing our new design;

FIG. 2 is a top view of the spherical toothbrush holder of FIG. 1;

FIG. 3 is a bottom view of the spherical toothbrush holder of FIG. 1;

FIG. 4 is a front view of the spherical toothbrush holder of FIG. 1;

FIG. 5 is a rear view of the spherical toothbrush holder of FIG. 1;

FIG. 6 is a right side view of the spherical toothbrush holder of FIG. 1;

FIG. 7 is a left side view of the spherical toothbrush holder of FIG. 1; and,

FIG. 8 is a perspective view of the spherical toothbrush holder of FIG. 1 shown in use.

The features shown in broken lines depict environmental subject matter only and form no part of the claimed design.

1 Claim, 6 Drawing Sheets(56)
